UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

RADIOSIGNALING SYSTEM.

1,320,959.

Specification of Letters Patent.

Patented Nov. 4, 1919.

Application filed October 16, 1917. Serial No. 196,958.

To all whom it may concern:

Be it known that I, ERNST F. W. ALEXANDERSON, a citizen of the United States, residing at Schenectady, county of Schenectady, State of New York, have invented certain new and useful Improvements in Radiosignaling Systems, of which the following is a specification.

My present invention relates to radio 10 signaling systems and particularly to means for transmitting radio signals by the use of continuous radio frequency currents.

In my prior applications, Serial No. 43,725, filed August 5, 1915; Serial No. 15 92,152, filed April 19, 1916, and Serial No. 189,495, filed September 4, 1917, I have described systems for transmitting radio signals by producing amplitude pulsations in a continuous radio frequency current supplied to a radiating antenna system. I have 20 in these applications shown that a continuous radio frequency current of a fundamental frequency having amplitude pulsations may be resolved into three components, one 25 of the fundamental frequency, one which has a frequency equal to the fundamental plus the frequency of the amplitude pulsations and a third of which has a frequency equal to the fundamental minus the frequency of 30 the amplitude pulsations.

One of the objects of my invention is to provide a transmitting system which will transmit signals of the class described most efficiently.

35 In attaining this object I tune the radiating system in such a way that instead of being in resonance for the fundamental frequency it is in resonance for one of the other frequencies into which the composite wave 40 may be resolved, preferably the component having a frequency equal to the fundamental plus the frequency of the amplitude pulsations. In the last named application I have shown how amplitude pulsations of several 45 different frequencies may be produced simultaneously. In this case the antenna will preferably be tuned for a frequency equal to the fundamental plus the highest frequency of amplitude pulsation employed. In case 50 the amplitude pulsations to be transmitted are produced by means of speech currents the antenna will preferably be tuned for a frequency equal to the fundamental plus the characteristic speech frequency which may 55 be taken as from 800 to 1000 cycles.

A radiating system operated in this way has the disadvantage that the fundamental wave is out of tune with the antenna and in case an alternator is used as a current source the load on the alternator will have a large 60 component of wattless current.

A further object of my invention is to overcome the above mentioned disadvantage and this object may be attained by tuning the alternator circuit for the fundamental 65 frequency.

The novel features which I believe to be characteristic of my invention are set forth with particularity in the appended claims. The invention itself, however, both as to its 70 organization and method of operation, together with further objects and advantages thereof will best be understood by reference to the following description taken in connection with the accompanying drawing in 75 which Figure 1 shows diagrammatically a circuit connection which may be employed in carrying my invention into effect and Fig. 2 shows by means of curves the relations between alternator currents and antenna current when the system operates in accordance 80 with my invention.

In the system indicated in Fig. 1 the antenna 1 is supplied with radio frequency current from the high frequency alternator 85 2, the terminals of which are connected to the points 3 and 4 of the antenna circuit. Connected in shunt to the alternator terminals is a magnetic amplifier 5 comprising a suitable core 6 of magnetic material and 90 two windings 7 and 8 as indicated. These windings are so arranged that the high frequency current supplied from the alternator flows through the two windings 7 and 8 in parallel and that the flux produced by this 95 current flows in opposite directions through the portions 9 and 10 of the core 6.

In order to adjust the magnetization of the core 6 to a point at which the device will operate most efficiently, direct current may 100 be supplied to the windings 7 and 8 from a generator 11 at the points 12 and 13, the strength of the current being regulated by a variable resistance 14. This current will flow through the two windings in series. 105 The points 12 and 13 are at the same potential with respect to the high frequency source and hence there is no tendency for high frequency current to flow through the circuit which supplies direct current to 110

windings 7 and 8. The condensers 15 and 16 which are in series with each of the windings 7 and 8 prevent the short circuiting of the direct current circuit.

5 In order to produce amplitude pulsations in the antenna current with the arrangement thus far described, it is only necessary to vary the controlling current in windings 7 and 8. I have in the present case illustrated one convenient method of simultaneously producing amplitude pulsations of three different frequencies for the transmission of three different messages. The alternators 17, 18 and 19 are designed to produce currents of three different frequencies lower than that of alternator 2, all of which if desired may be within the range of audibility. For example, alternator 17 may give 800 cycles, alternator 18, 700 cycles, and alternator 19, 600 cycles. Poles 20, 21 and 22 of these alternators are connected directly to the circuit which supplies direct current to windings 7 and 8 and poles 23, 24 and 25 are connected to that circuit 25 through keys 26, 27 and 28, respectively. If the alternators have the frequencies mentioned, when key 26 is closed 800 cycle current will be supplied to windings 7 and 8 and a message transmitted by key 26 will 30 be transmitted by means of amplitude pulsations having a frequency of 800. Similarly a second message may be transmitted simultaneously by key 27 by means of amplitude pulsations having a frequency of 700, and 35 a third message may be transmitted by key 28 by means of amplitude pulsations having a frequency of 600. The operation of the control apparatus may be improved by the use of a condenser 29 in series with windings 7 and 8, and so adjusted that the circuit in which it is included becomes resonant 40 when the antenna current is a minimum.

I have shown in my prior applications referred to above that a wave of fundamental 45 frequency having amplitude pulsations may be resolved into three components and that if any two of these components are transmitted they may be combined at the receiving station to produce a wave of fundamental frequency with amplitude pulsations 50 of the frequency produced at the receiving station. If, however, the antenna is tuned to the fundamental frequency the component corresponding to that frequency will be 55 transmitted with a maximum amplitude and the amplitude of the other components will be so low that the amplitude pulsations produced at the receiving station by the combination of the components will be of 60 small magnitude in comparison with the total current received. This disadvantage 65 may be overcome by adjusting the tuning of the antenna circuit by means of the usual variable inductance 30 so that it is resonant for a frequency equal to the highest fre-

quency component of the amplitude pulsations. For example, in the case described in connection with Fig. 1 the antenna circuit may be tuned to a frequency equal to the fundamental plus 800. Then assuming 70 that the dotted curve of Fig. 2 represents the tuning curve of the antenna, the component which has a frequency equal to the fundamental plus 800 may fall at the point A, the component which has a frequency 75 equal to the fundamental plus 700 may fall at the point B, the component which has a frequency equal to the fundamental plus 600 may fall at the point C and the component having a frequency equal to the fundamental may fall at the point D.

In case the amplitude pulsations are produced by means of speech currents, it will be desirable to tune the antenna circuit to a frequency equal to that of the fundamental 80 wave plus approximately 1000 cycles as the representative higher harmonics of the voice have a frequency of from 800 to 1000 cycles. The distortion of speech over telephone lines has been largely overcome by tuning the 85 lines for this frequency so that the amplification of the higher harmonics by tuning compensates the tendency which the line would otherwise have to suppress the harmonics. By tuning the antenna for a frequency 90 1000 cycles greater than that of the fundamental wave employed, a result may be attained which is equivalent to tuning a wire line for the higher harmonics of the 95 voice.

It will be apparent, however, that if the antenna is tuned for a frequency higher than that of the fundamental wave, the alternator can not deliver as much power as it could if the antenna was resonant to the 100 fundamental frequency. The antenna load on the alternator becomes equivalent to a condenser load and the alternator will work at a very low power factor. One apparent way to overcome this disadvantage would 105 be to neutralize the capacity load of the antenna by means of inductance. If this were done, however, in the most obvious way, the desired result would not be secured because the antenna tuning would be changed 110 so that it would be in resonance with the alternator frequency. I have found that the desired correction may be obtained by tuning the alternator circuit. The alternator will deliver its maximum output when 115 the inductive reactance of its circuit is balanced by an equal capacity reactance. In the present case this may be accomplished by means of a variable condenser 31 in the alternator circuit which is so adjusted as to 120 neutralize the internal inductance of the alternator. Across the terminals of the tuned alternator circuit is placed an inductance 32 which is so adjusted that it neutralizes the wattless component of the an- 125 130

5 antenna current which has the character of a condenser load. This inductance is so chosen that the resulting resonant voltage of the antenna across the terminals of the alternator circuit is equal to the energy voltage which the alternator can deliver at unity power factor. If this adjustment is properly made the alternator will deliver current at unity power factor to the oscillating antenna circuit although the antenna is not in tune with the alternator. The shunt inductance when used this way will have practically no effect upon the antenna tuning but it will neutralize the capacity load of 10 the alternator and allow it to deliver energy at substantially unity power factor. The effect of this arrangement is indicated in Fig. 2. An inspection of this figure will show that although the antenna is not resonant to the alternator frequency, the alternator will deliver its maximum current when the antenna current is a maximum.

20 While I have illustrated and described a single embodiment of my invention, I do not wish to be limited to the specific circuit arrangement shown, as it will be apparent that many variations may be made in the circuit arrangements and the apparatus employed without departing from the scope of 25 my invention as set forth in the appended claims.

What I claim as new and desire to secure by Letters Patent of the United States, is,—

1. A system for transmitting radio signals 35 comprising a source of continuous radio frequency current of a definite frequency, means for producing amplitude pulsations in the current derived from said source and a radiating antenna supplied with current 40 from said source and tuned for resonance at a frequency equal to that of the source plus the most important frequency of the amplitude pulsations.

2. The method of transmitting radio signals 45 which consists in producing amplitude pulsations corresponding to the signals to be transmitted in a continuous radio frequency current and supplying the current having amplitude pulsations therein to a 50 radiating antenna system which is resonant to a frequency equal to the frequency of the source plus the frequency of the most important amplitude pulsations.

3. A system for transmitting radio signals 55 comprising a source of continuous radio frequency current, a radiating antenna system supplied with energy from said source and tuned for resonance to a frequency which is materially different from that of 60 the source and means for adjusting the system in such a way that the current supplied by the source is substantially in phase with the electromotive force.

4. A system for transmitting radio signals 65 comprising a source of continuous radio

frequency current, a radiating antenna system which is resonant to a frequency which is materially different from that of the source and a circuit for supplying energy from said source to said antenna, the combined energy supply circuit and antenna being resonant to the frequency of said source. 70

5. A system for transmitting radio signals comprising a source of continuous radio frequency current, a radiating antenna, 75 a local circuit for supplying current from said source to said antenna, and means for producing amplitude pulsations in the current in said antenna, said local circuit being resonant to the frequency of the source, 80 and said antenna being resonant to a frequency equal to the frequency of the source plus that of the most important amplitude pulsations of the current therein.

6. The combination in a system for transmitting signals by means of high frequency continuous waves having amplitude pulsations, of a resonant transmitting circuit, a source of continuous high frequency current adapted to supply energy to said transmitting circuit, and means for tuning the circuit supplied by said source so that the current and voltage supplied by said source are in phase at a different frequency from the resonant frequency of the transmitting circuit. 85 90 95

7. The combination in a signaling system of a source of high frequency alternating current, a signal transmitting circuit which is resonant to a frequency which is different from that of the source, means for producing amplitude pulsations corresponding to signals in the current supplied from said sources of said signal transmitting circuit, and means for tuning the system in such a way that the current supplied by the source 100 105 is substantially in phase with the electromotive force.

8. The combination in a signaling system of a source of high frequency alternating current, a signal transmitting circuit which is resonant to a frequency different from that of said source, a local circuit connecting said source to said signal transmitting circuit which is resonant to the frequency of said source, and a reactance in shunt to said local circuit for balancing the reactance of the signal transmitting circuit so that the current supplied by the source will be substantially in phase with the electromotive force. 110 115 120

9. The combination in a signaling system of a high frequency alternator, a signal transmitting circuit which is resonant to a frequency which is different from that of the current supplied by said alternator, a local circuit for supplying current from said alternator to said signal transmitting circuit, a capacity in said local circuit for neutralizing the internal inductance of the alternator, and a reactance in shunt to said 125 130

local circuit and said signal transmitting circuit for balancing the reactance of the latter so that the current supplied by the source will be substantially in phase with 5 the electromotive force.

10. The combination in a signaling system of a source of continuous radio frequency current of a definite frequency, means for producing amplitude pulsations 10 in the current derived from said source, a signal transmitting circuit supplied with current from said source and tuned for

resonance at a frequency equal to that of the source plus the most important frequency of the amplitude pulsations, and an inductance in shunt to said source and said transmitting circuit for neutralizing the capacity reactance of the transmitting circuit so that the current supplied by the source will be substantially in phase with the elec- 15 trömotive force.

In witness whereof, I have hereunto set my hand this 15th day of October, 1917.

ERNST F. W. ALEXANDERSON.
